UNITED STATES PATENT OFFICE.

CHARLES GRAHAM, OF BROOKLYN, NEW YORK.

DESIGN FOR A LEG FOR SLOP-TUBS.

SPECIFICATION forming part of Design No. 24,058, dated February 19, 1895.

Application filed December 5, 1894. Serial No. 530,923. Term of patent 14 years.

To all whom it may concern:

Be it known that I, CHARLES GRAHAM, a citizen of the United States, residing in Brooklyn, Kings county, in the State of New York, 5 have invented and produced a new and original Design for a Slop-Tub Leg, of which the following is a specification, reference being had to the accompanying drawing, forming a part thereof.

10 *c* The leading feature of my design consists in a leg or upright, with a spread top, extended upward at the outer edge, all made ornamental.

15 D is an upright leg; D', is a broad head thereof and D² is a thin extension upward from the outer edges thereof. The under side of the head is contracted trumpet wise, as indicated by D³. It is smooth except as hereinafter indicated. Below this the leg is increased in diameter, with a slight offset D⁴, below which is a narrow swell or bead D⁵, of 20 a diameter approximating, but less than that of the head D'. This bead is divided circumferentially into sections by grooves D⁶, 25 extending up and down in pairs, inclosing narrow beads between. Below this divided swell D⁵, D⁶, is another small vertical offset D⁷, beneath which is a concave groove D¹⁰. At the lower edge of this groove is another 30 vertical offset D¹¹, below which is a bead or collar of rectangular section D¹²; and below this is a contraction formed with a horizontal series of beads or spheroidal swells D¹³. Below this is a considerable portion of the length 35 of the leg, D¹⁴, D¹⁵, the upper portion D¹⁴ being approximately hemispherical, and the lower portion D¹⁵ prolonged downward, gradu-

ally contracting, slightly swelled and heavily fluted. The longitudinal grooves by which the fluting is effected are approximately semi-circular in cross section. Next below the long portion D¹⁵, just described, is a stepped collar D¹⁶, and below this a nearly cylindrical further extension downward D¹⁷, having quick helical grooves D¹⁸, giving a twisted effect. 45 Below this is a slight collar D¹⁹. Below this is an approximately spheroidal ornament, which I will designate collectively by D². Its surface is divided by grooves D²⁰ extending up and down. The surface between these 50 grooves is approximately spheroidal, forming a series of swelled segments D²¹. The upward extension D² is approximately semi-circular. Its outer face is decorated with an inverted duplex scroll D²², having its stem in the center of the top and its terminations in the right and left hand corners of the bottom. The center of the bottom presents a row of beads extending downward on the contracted under face D⁵ of the head. The remaining surface 55 of the upward extension D² is covered with upright foliated ornaments D²³.

What I claim as new, and desire to secure by Letters Patent, is—

The design for a slop-tub leg herein shown 60 and described.

In testimony that I claim the invention above set forth I affix my signature in presence of two witnesses.

CHAS. GRAHAM.
